TABLET DISPENSER

Michael Taterka, Waukegan, Ill., assignor to Abbott Laboratories, Chicago, Ill., a corporation of Illinois

Application December 18, 1958, Serial No. 53,816

Term of patent 14 years

(Cl. D58—12)

Fig.1

I claim:

The ornamental design for a tablet dispenser, substantially as shown.
